UNITED STATES PATENT OFFICE

2,626,487

CHAIN AND GEAR DRIVEN SEMIAUTOMATIC
BUFFING MACHINE

Anthony J. Janusauskas, Waterbury, Conn.

Application July 20, 1950, Serial No. 174,948

1 Claim. (Cl. 51—76)

1

This invention relates to buffing machines, and more particularly to a machine having a conveyor which will carry the work past a buffing wheel in such a manner that all outer surfaces of the work will be subjected to the action of said buffing wheel.

One object of this invention is to provide a machine of the above nature in which no manipulation of the work on the part of the operator will be required other than to place it on and remove it from the conveyor.

Another object is to provide a machine of the above nature in which the work will be carried past the buffing wheel in a direction which is oblique to the axis of the wheel, whereby the end surfaces of the work may be effectively buffed.

Another object is to provide a machine of the above nature in which a substantially universal adjustment of the conveyor will be obtainable with respect to the wheel, whereby the machine may be readily adapted to different operating conditions.

A further object is to provide a machine of the above nature which will be simple in construction, inexpensive to manufacture, easy to install and operate, compact, and very efficient and durable in use.

With these and other objects in view, there has been illustrated on the accompanying drawings one form in which the invention may conveniently be embodied in practice.

In the drawings,

Fig. 1 is a front view showing the improved buffing machine as it would appear when in use for buffing elongated pencil caps.

Fig. 2 is a plan view of a right-hand end portion of the machine.

Fig. 3 is a left-hand end view of a portion of the machine, showing the conveyor frame and means for supporting and adjusting said frame.

Fig. 4 is a cross-sectional view, taken substantially on the line 4—4 of Fig. 2, but on an enlarged scale, showing the relationship of the work to the buffing wheel at one stage of the buffing operation.

Fig. 5 is a side view, partly in section, of the work-supported mandrel and its rotatable mounting.

Referring now to the drawings, in which like reference numerals denote corresponding parts throughout the several views, the numeral 10 indicates generally a conveyor frame which comprises longitudinally extending upper and lower plates 11, 12 and pairs of uprights 13, 14 joining the sides of said plates adjacent their ends.

In order to support the conveyor frame 10 ad-

2

justably, the respective corners thereof are provided with vertical adjusting screws 15, two of said screws being held in lateral ears 16 on the lower plate 12 at the left-hand end of the frame, 5 and another pair of said screws being held in flanged downward extensions 17 of the uprights 14 at the opposite right-hand end of said frame.

The lower ends of the adjusting screws 15 rest in slotted transverse base members 18, 19, which 10 are adapted to be secured to the floor F by means of a plurality of bolts 20. Thus, it will be seen that the conveyor frame 10 may readily be supported in a position which is slightly inclined in an upward direction from the left to the right-hand end thereof. The inclination of said frame 15 may be adjusted in both longitudinal and lateral directions by proper manipulation of the adjusting screws 15.

As a means for adjustably holding the conveyor frame 10 against shifting in a lateral direction, the base members 18, 19 are provided with respective pairs of fixed standards 21, 22 which are located outwardly of the respective uprights 13, 14, each of said standards having an upper horizontal adjusting screw 23 and a lower horizontal adjusting screw 24. Inasmuch as the inner ends of the adjusting screws 23, 24 are adapted to engage the outer surfaces of the uprights 13, 14, it will be seen that the conveyor frame 10 may be held securely against accidental lateral shifting, while said frame may upon proper manipulation of said adjusting screws 23, 24 be adjusted laterally as desired.

The opposite end portions of the conveyor frame 10 are provided with parallel upright shafts 25, 26 which extend at right angles to the upper and lower conveyor plates 11, 12, and which are rotatably mounted in a plurality of bearings 27 in said plates. The shafts 25, 26 extend above the upper conveyor plate 11 and are provided with respective sprockets 28, 29 around which a conveyor chain 30 is engaged for movement in a plane parallel to the conveyor frame plates 11 and 12.

45 The conveyor chain 30 comprises apertured links arranged in three longitudinal series 31, 32, 33 which are swingably connected by a plurality of vertical pins 34, the links of the respective series being held in spaced parallel relationship by means of bushings 35 on said pins.

In order to support a plurality of spindle carriers 36, alternate links 37 of the upper link series 31 and alternate links 38 of the lower series 33 are provided respectively with outwardly extending apertured ears 39, 40. It will be noted, however, that the upper and lower ears 39, 40 are

respectively staggered so that the spindle carriers 36 will be held in forwardly inclined positions when inserted in said ears.

Each of the spindle carriers 36 is provided with a flange 41 (Fig. 5) at its upper end for supporting it in a pair of the apertured ears 39, 43, and is formed with a longitudinal bore 42 for rotatably receiving a stem 43 of a work-supporting spindle 44. The bottom of each bore 42 preferably has a ball-bearing 45 against which the lower end of the stem 43 is engaged, and which will minimize the friction due to rotation of said stem. The upper end 46 of each spindle 44 is preferably of such a size and shape as to conform to the inner contour of the work article, which in this case is shown as an elongated tapered pencil cap W.

Provision is made of a suitable buffering wheel 47 which is mounted upon a horizontal shaft 48 and which is so located as to perform a buffering or polishing operation upon the pencil caps W as they are moved past said wheel by the conveyor chain 30.

Inasmuch as the chain 30 moves past the buffering wheel 47 in a downwardly inclined direction from right to left, as viewed in Figs. 1 and 2, it will be noted that the wheel 47 will first engage the lower end portions of the caps W after which the buffering will progress upwardly to the top of said caps before said caps leave the zone of the buffering operation. This construction permits caps or other articles of greater length than the contact area of the buffering wheel to be buffed. However, in order to permit the buffering wheel 47 to operate upon all sides of the caps W, provision is made of means for turning said caps, said means comprising cylindrical rollers 49 which are integrally formed upon central portions of each of the spindles 44. As the spindles 44 approach the buffering wheel 47, the rollers 49 will enter into engagement with an outer edge portion 50 of a guide member 51, said outer edge portion extending past the buffering wheel 47 so that the spindles 44 and the work W will be continuously rotated throughout the buffering operation.

The guide member 51 is supported at a level above the conveyor chain 30 by means of an upstanding post 52 on the upper conveyor frame plate 11, said post having a channeled upper end 53 in which an arm portion 54 of the guide member 51 is adjustably held by means of a bolt 55.

The construction of the upper end 53 of the post 52 is such that the guide plate 51 may, upon loosening of the bolt 55, be adjusted toward or away from the buffering wheel 47, thus controlling the degree of pressure with which the edge portion 50 engages the rollers 49, and also, because of the flexibility of the conveyor chain 30, permitting the line of movement of the spindles 44 to be adjusted somewhat with respect to the buffering wheel.

The buffering wheel shaft 48 will be supported and driven by any suitable driving means within a stand 56 which is secured to the floor F by bolts 57.

The conveyor chain 30 is adapted to be driven by a variable speed motor 58 mounted upon the lower frame plate 12 and having a pinion 59 meshed with a bevel gear 60 fixed upon the left-hand sprocket shaft 25.

If desired, the upper frame plate 11 may be provided with an idler roller 61 for eliminating shock in the conveyor chain 30.

4 Operation

In use, the conveyor chain 30 and the buffering wheel 47 will first be placed in operation and pencil caps or other work W will be placed upon each of the spindles 44 so as to be carried past the buffering wheel 47 in a direction from right to left, as viewed in Figs. 1 and 2.

Inasmuch as a major portion of the conveyor chain 30 is located to the left of the buffering wheel 47, the operator will be afforded ample opportunity to remove the caps W which have been buffed and to apply unbuffed caps W to the upper ends 46 of said spindles. The vertical frame adjusting screws 15 will, of course, be so adjusted as to support the conveyor chain 30 in an inclined position in which the buffering wheel 47 will first act upon the lower end portions of the caps W and thereafter buff the entire length of said caps.

As the caps W progress across the face of the buffering wheel 47, the point of maximum active buffering action will progress upwardly to the tips of the caps W, said caps being automatically rotated at the same time because of the engagement of the rollers 49 with the guide member 51, so that all parts of the outer surfaces of the caps W will be efficiently buffed.

If it should be found desirable to bring the narrow tips of the caps W into closer engagement with the buffering wheel 47, the frame adjusting screws 15 may be manipulated so as to tilt the conveyor frame 30 toward said wheel.

The horizontal frame adjusting screws 23, 24 will, of course, control the horizontal location of the path in which the caps W are moved across the base of the buffering wheel 47. This path preferably will be convergent with the axis of the buffering wheel when tapered objects are being buffed, so that said wheel may have a more efficient action upon the narrow tips of the work.

Any suitable polishing or abrasive compounds may be applied to the buffering wheel 47, and preferably a relatively coarse buffering compound will be applied to a zone of the wheel which is first engaged by the work. A finer grade of polishing compound may be applied to the remainder of said wheel so as to impart a final polish to the work. Thus, it will be seen that each of the pencil caps W will be completely buffed over its entire surface in a single pass across the front of the buffering wheel 47.

It will be understood that the buffering machine herein disclosed is not limited to the buffering of pencil caps, but will also be adapted to buff articles of other shapes merely by providing suitable spindles for supporting the work and manipulating the adjusting screws 15, 23, and 24, so as to cause the work to move in the proper path across the face of the buffering wheel 47.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claim.

Having thus fully described the invention, what is claimed as new and for which it is desired to secure Letters Patent, is:

In a buffering machine, a buffering wheel mounted to rotate on a horizontal axis, a continuously-driven endless conveyor chain for carrying tubu-

lar articles to be buffed across the surface of said buffing wheel in a downwardly inclined rectilinear path, whereby the buffing of said articles will progress from the bottoms to the tops thereof, the articles to be buffed being supported on upstanding inclined spindles, rotatably mounted on said chain, a stationary guide plate in the path of said spindles and adapted to be successively engaged thereby, whereby said articles will be continuously rotated while being buffed, and means for adjustably tilting said conveyor and guide plate toward and away from said buffing wheel.
